TRAY ATTACHMENT FOR A GOLF CART

John W. Bailey, Van Nuys, Calif.

Application November 18, 1957, Serial No. 48,509

Term of patent 14 years

(Cl. D34—5)

Fig. 2.

Fig. 1 is a perspective view of a tray attachment for a golf cart showing my new design.

Fig. 2 is an edge view as seen from the rear of Fig. 1.

I claim:

The ornamental design for a tray attachment for a golf cart, substantially as shown.
